UNITED STATES PATENT OFFICE.

HENRY O'B. HARDING, OF MINNEAPOLIS, MINNESOTA, ASSIGNOR TO WASHBURN-CROSBY COMPANY, OF MINNEAPOLIS, MINNESOTA, A CORPORATION OF MINNESOTA.

AUTOMATIC CONTROLLING MECHANISM FOR FLOUR-PACKING MACHINES.

Application filed June 1, 1920. Serial No. 385,566.

To all whom it may concern:

Be it known that I, HENRY O'B. HARDING, a citizen of the United States, residing at Minneapolis, in the county of Hennepin and State of Minnesota, have invented certain new and useful Improvements in Automatic Controlling Mechanism for Flour-Pack ing Machines, of which the following is a specification.

This invention relates to flour packing machines of the type illustrated described and claimed in an application for Letters Patent of the United States filed by me June 1, 1920, Serial No. 385,565.

The present invention is concerned more particularly with means for controlling the operation of the machine referred to, and its main and primary object is to so construct the machine that its operation, after the initial starting thereof, will continue automatically and without further attention by the operator except to feed and position properly the empty bags or sacks to be filled, and to remove the individual bags or sacks after the filling operation has been completed.

The invention further aims to provide controlling mechanism of the character mentioned which is positive in action; one wherein in the operative parts are so organized and related as to be readily accessible for repair when such is required, and easily replaceable in the event of damage; and finally a controlling mechanism which will require but minimum power for its operation in addition to that required for operation of the machine in the performance of its packing function.

The invention seeks also to attain other objects and advantages which will appear as the nature of the improvements is better understood, the invention consisting substantially in the novel construction, combination and arrangement of parts hereinafter fully described, illustrated in the accompanying drawings and finally pointed out in the appended claims.

One form of the invention is disclosed herein by way of illustrating its practical embodiment, but this is not to be taken in a limiting or restrictive sense, the same serving to delineate an appropriation of the concept to the purposes for which the invention is intended.

In the drawings—

Fig. 1 is a front elevation of a flour packing machine wherein is incorporated an automatic controlling mechanism constructed in accordance with the present invention;

Fig. 2 is a side elevation thereof;

Fig. 3 is a detail perspective view, on an enlarged scale, of the clutch mechanism forming part of the automatic control, together with the means for actuating the same.

The flour packing machine with which the herein-described automatic controlling mechanism is employed is made the subject-matter of the application for Letters Patent of the United States filed June 1, 1920, Serial No. 385,565, hereinbefore referred to. It will, therefore, be unnecessary to describe in detail that machine, but the general features thereof will be pointed out for a comprehensive understanding of the relation of the controlling mechanism herein disclosed to those particular features. Referring, therefore, in detail to the accompanying drawings, the numeral 10 designates a pair of vertical supporting standards which comprise a part of the frame-work. Between these standards is located a feed-hopper 11 to the upper portion of which is connected a supply chute 12 leading from an elevated source of the flour to be packed. The feed of the flour from the chute 12 to the hopper 11 is controlled by a sliding gate 13 actuated by an operating lever 14 suitably connected thereto.

At the head of the supporting standards 10 and disposed at opposite sides of the frame is a pair of horizontal supporting rails 15, which rails preferably are formed of angle iron. Passing through the chute 12, in parallel relation with the rails 15, but at a point above the same, is a line shaft 16 from which power is derived for driving the machine. A worm-gearing 17 is arranged at one side of the chute 12 and serves to transmit power from the shaft 16 to an intermediate shaft 18 the ends of which are journaled in suitable bearings carried by the supporting rails 15, said shaft 18 thus being arranged transversely of said rails. At the opposite side of the chute 12, and located at the upper portion of the machine frame, is a feed clutch mechanism 19 connected to a packing shaft 20 disposed verti-

cally of the machine, said clutch mechanism 19 providing an intermediate driving connection between the packing shaft 20 and the line shaft 16. The shaft 20 passes downwardly through the feed-hopper 11, and within the latter said shaft is equipped with a plurality of packing augers (not shown) which serve to force the flour or other material downwardly through the hopper 11 at the lower end of which is arranged a discharge nozzle 21. The bag to be filled is applied to the lower end of said discharge nozzle, and the packing augers within the hopper 11 serve to force the flour downwardly into the bag arranged on the nozzle 21 in which the flour is compactly pressed as the bag is filled.

The numeral 22 designates a bag supporting carriage which is mounted for vertical movement between the frame members 10. This includes a horizontally disposed shelf 23 on which the bag to be filled is supported, and said carriage 22 is connected to a plurality of counter-weights by means of a sprocket chain 24 which is trained over a sprocket wheel 25 mounted on a controlling shaft 26 which is journaled on the machine frame and arranged at the rear of the feed-hopper 11. Rotation of the controlling shaft 26 is retarded by friction mechanism 27, and when the action of this friction mechanism is removed from said shaft 26 its speed of rotation is increased by accelerating mechanism 28 in order to give to the carriage 22 a quick downward movement after the bag has been filled.

For manually starting the packing shaft 20 and the augers carried thereby an operating lever 29 is employed. This is pivoted to a connecting rod 30 which extends upwardly and has its upper end pivotally connected to an actuating arm 31 which, in turn, is connected to the clutch mechanism 19 and by which the driving relation of said clutch mechanism to the driving shaft 16 is controlled.

The elements of construction above described constitute generally the main features of the flour packing machine for the control of which the herein-described mechanism is designed. The purpose of the present mechanism is to afford an automatic control of the machine in question, thus relieving the operator of the necessity for starting the machine at the filling of each individual bag. To the attainment of this end a control shaft 32 is arranged at the head of the machine in proximity to the feed clutch mechanism 19. Normally this shaft does not rotate; that is to say, it remains inactive until the supporting carriage 22 is elevated to a point where the bag to be filled is held in proper relation to the discharge nozzle 21 of the hopper 11. To maintain the control mechanism inactive the

carriage 22, at the upper end of one of its sides, is provided with an outwardly extending engaging lug 33. Pivotally mounted on the adjacent supporting member of the frame, as by a bracket 34, is an L-shaped locking pawl 35 having a handle 36 by which the pawl may be swung into and out of the path of engaging lug 33. When positioned over the engaging lug 33 the pawl 35 prevents upward movement of the carriage 22 to the full limit of its movement in such direction, and the controlling mechanism, therefore, is prevented from operating. When, however, the pawl 35 is swung out of the path of said lug 33 the carriage 22 may move to its full limit of upward movement, and the controlling mechanism then becomes operative as will presently appear.

Arranged at the upper end of the side of the carriage 22 opposite to that whereon the engaging lug 33 is positioned is an attaching bracket 37 in which is journaled a contact roller 38. The roller 38 is designed to engage and move over an inclined contact face 39 formed at the lower end of a clutch shifting lever 40. This lever has its upper end fulcrumed, as at 41, to an overhanging arm 42 formed on a bearing bracket 43 in which one end of the control shaft 32 is mounted for rotation. The bearing bracket 43 is carried by one of the frame members at the head of the machine. Suitably connected to the upper portion of the shifting lever 40 is a clutch member 44 which is mounted to rotate with the shaft 32 but capable of sliding movement thereon. The clutch member 44 cooperates with a second clutch member 45 which is loosely mounted on the shaft 32 and to which a driven pulley 46 is connected. This pulley preferably receives its power from the shaft 18 actuated by the worm-gearing 17 which is connected to the line shaft 16. When the clutch member 44 is engaged with the clutch member 45 the shaft 32 is coupled with the pulley 46 and driven thereby. This pulley rotates constantly so long as the line shaft 16 is in operation.

Fixedly connected to the control shaft 32 at the end opposite to that on which the pulley 46 is mounted is a double groove worm-sleeve 47, and associated with said worm-sleeve is a traveller-sleeve 48 at the upper portion of which is located a guide lug 49. The lug 49 is arranged between a pair of parallel guides 50 which are carried by a bearing 51 through which the shaft 32 passes. The guides 50 are arranged above the worm-sleeve 47, and the traveller-sleeve 48 is thus maintained properly supported in relation to said worm-sleeve for travel longitudinally thereof. Depending from the worm-sleeve 48 is an inclined contact shoe 52 which cooperates with a con-

tact head 53 carried by the actuating lever 31 of the feed clutch mechanism 19. As the control shaft 32 is rotated the worm-sleeve 47 causes the traveller-sleeve 48 to move inwardly or towards the feed clutch mechanism 19. As the shoe 52 advances its inclined surface rides upon the contact head 53 and depresses the same, and this depression actuates the arm 31 to operate the feed clutch mechanism 19 for establishing driving connection between the line shaft 16 and the packing shaft 20. This expels the flour from the discharge nozzle 21 into the bag surrounding the same, the bag thus being filled, and causing downward movement of the carriage 22 so that the bag may be positioned for removal from the carriage 22 when the filling operation is completed. When the traveller-sleeve 48 reaches the limit of its inward movement on the worm-sleeve its direction of travel is reversed by the reversely arranged groove of said sleeve, and this causes the shoe 52 to move in an outward direction or away from the feed clutch mechanism 19. In this outward movement it will be seen that the lever 31 is free to move upwardly, and this upward movement is induced by a coil spring 54 which is connected to the rod 30 and the machine frame. This occurs after the bag has been filled, and when said lever 31 is thus actuated the packing shaft 20 is brought to rest and no further discharge of the flour from the nozzle 21 take place until a new empty container is placed thereon and the shoe 52 again moved inwardly to actuate the feed clutch mechanism 19.

At the lower end of the clutch-shifting lever 40 is located a horizontally disposed outwardly extending locking lug 55 having an inclined toe 56. A latch lever 57 is pivotally connected, as at 58, to the adjacent frame member 10, and the inner end of said latch lever is designed to engage the locking lug 55 in rear of the inclined toe 56. The inner end of said latch-lever 57 is appropriately shaped for such engagement. The outer end of the lever 57 is connected to a link 59 the upper end of which is pivoted to the horizontal arm 60 of a bell-crank lever pivoted, as at 61, to the overhanging arm 42. The vertical arm 62 of said bell-crank lever is pivoted to a push-rod 63, said push-rod being pivoted to a crank arm 64 carried by a rock shaft 65 mounted in a vertical support 66 in which the extremity of the shaft 32 is journaled. Depending from said rock shaft 65 is a contact arm 67 the lower extremity of which is in the path of movement of the traveller-sleeve 48 on its outward stroke. Thus it will be seen that when the latch lever 57 is engaged by the locking lug 55 the shifting lever 40 is held in such position that the clutch members 44 and 45 are engaged, and this im-

parts continuous rotation to the shaft 32 so long as this engagement continues. The latching of the lever 57 with the lug 55 is made possible by the outward movement of the lower end of the lever 40 induced by contact of the roller 38 with the inclined contact face 39 on the upward movement of the carriage 22. When, however, the carriage 22 moves downwardly and the roller 38 is removed from cooperative relation with the inclined contact face 39, the lower end of the shifting lever 40 is retained in its outer position by engagement of the lug 55 by the latch lever 57. Release of the lever 40 from the latch 57 does not occur until after the bag has been filled, and such release takes place when the traveller-sleeve 48 has moved outwardly away from feed clutch mechanism 19 into contact with the lever 67, whereupon the shaft 65 is rocked, the crank arm 64 moves inwardly thus rocking the bell-crank lever connected to the push-rod 63, and the link 59 moves downwardly. This depresses the outer end of the latch lever 57, resulting in a release of its inner end from the engaging lug 55, and a disengagement of the clutch member 44 with respect to the member 45 ensues. As this brings the shaft 32 to rest there is no further inward movement of the shoe 52 for actuating the feed clutch mechanism 19 until the bag supporting carriage 22 again moves upwardly to swing the clutch shifting lever 40 outwardly by reason of contact of the roller 38 with the inclined contact face 39.

From the foregoing description it will be obvious that so long as the upward movement of the carriage 22 to its full limit is not prevented by engagement of the lug 33 with the locking pawl 35 the flour packing machine will operate automatically for the filling of successive bags as they are presented to the machine and removed therefrom after the filling operation. The operator is required only to apply the empty bag or sack to the discharge nozzle 21 and remove the same, when filled, from the carriage 22 after the latter has been moved downwardly away from said nozzle. The rise of the carriage and its cooperation with the clutch-shifting lever 40 starts operation of the packing shaft 20 and its augers within the discharge hopper 11, and its movement downwardly from the lever 40 enables free movement of this lever when the latch lever 57 is released from its engagement at the time the traveller-sleeve 48 reaches its outward limit of movement.

It will be observed that by virtue of the control mechanism above described the extent of operation of the feeding mechanism for filling each receptacle is positively predetermined, that is, the feed shaft 20 will be operated a certain number of revolutions in

each period of operation. This secures a feed of a uniform amount of material into each receptacle, irrespective of variations in the size of the receptacles. In the filling of bags particularly, this is of distinct advantage, as such receptacles are likely to vary materially in capacity, due both to inaccuracies in their manufacture and to their stretching during the packing operation. 10 By virtue of the control mechanism constituting the present invention the feeding of the material will be stopped automatically as soon as the desired quantity is deposited in the receptacle, and the operation of the machine will continue automatically from that point to position the filled receptacle for removal and to position the carriage for the filling of the succeeding receptacle.

I claim:

26 1. In a machine of the class described, the combination with means for feeding the material to be packed, of a support for the bag to be filled movable towards and away from said feeding means, driving mechanism, a 25 control shaft, starting mechanism associated with said control shaft for initiating operation thereof when the bag support is moved towards the feeding means, mechanism operated by said control shaft for establishing 30 driving relation between the driving mechanism and the feeding means, and means operable through instrumentality of the control shaft to disconnect it and the feeding means from said driving mechanism 35 upon a predetermined extent of operation of the control shaft.

2. In a machine of the class described, the combination with means for feeding the material to be packed, of a support for the bag 40 to be filled movable towards and away from said feeding means, a control shaft, driving mechanism for operating said control shaft and the feeding means, clutch mechanism for connecting the driving mechanism with 45 said control shaft for driving the latter, means operable by the support for locking the clutch mechanism in driving relation to said control shaft, feed control means actuated by said control shaft to connect the 50 driving mechanism with the feeding means, and means operated by the feed control means for disconnecting the driving mechanism from said feeding means.

3. In a machine of the class described, the 55 combination with means for feeding the material to be packed, of a support for the bag to be filled movable towards and away from said feeding means, driving mechanism for said feeding means, a control shaft, 60 clutch mechanism associated with said control shaft for controlling operation thereof, means actuated by the movement of the bag support towards the feeding means for locking 65 said clutch mechanism in driving relation to said control shaft, a controlling de-

vice operated by said control shaft for controlling the driving mechanism, whereby to connect the same with the feeding means when the bag support is moved towards the latter and to interrupt said connection after 70 predetermined operation of said feeding means, and means actuated by said controlling device for disengaging said clutch mechanism from said locked relation to said control shaft.

4. In a machine of the class described, the combination with means for feeding the material to be packed, of a support for the bag to be filled, movable towards and away from said feeding means, driving mechanism for 80 said feeding means, a control shaft, clutch mechanism associated with said control shaft for controlling operation of the same, means controlled by the bag support on its movement towards the feeding means for locking 85 the clutch mechanism in engagement with said control shaft, a reciprocating traveller associated with said control shaft and operatively related to the driving mechanism to connect the latter with the feeding means in 90 one direction of movement of said traveller, and means operated by said traveller in its other direction of movement for permitting disengagement of the clutch mechanism from said control shaft.

5. In a machine of the class described, the combination with means for feeding the material to be packed, of a support for the bag to be filled, driving mechanism for said feeding means, a control shaft, clutch mechanism associated with said control shaft for controlling operation of the same, a shifting lever associated with said clutch mechanism and actuated by the bag support on its movement towards the feeding means to engage 100 the clutch mechanism with said control shaft, means for locking said shifting lever to maintain the engaged relation of the clutch mechanism with said control shaft, a reciprocating traveller associated with said control shaft and operatively related to said driving mechanism to connect the latter with the feeding means on one direction of movement of said traveller, and means actuated by said traveller on the other direction of its movement to permit release of the shifting lever to disengage the clutch mechanism from said control shaft.

6. In a machine of the class described, the combination with means for feeding the material to be packed, of a support for the bag to be filled movable towards and away from said feeding means, driving mechanism for said feeding means, a control shaft, clutch mechanism associated with said control shaft for controlling operation thereof, a shifting lever adapted to be actuated by the bag support on its movement towards the feeding means for operating said clutch mechanism to engage the latter with said control shaft,

- a latch lever for engaging said shifting lever to lock the clutch mechanism in engagement with said control shaft, a reciprocating traveller associated with said control shaft, a contact shoe carried by said traveller, an actuating lever associated with said driving mechanism and adapted to be engaged by said contact shoe to connect the driving mechanism with the feeding means on one direction of movement of the reciprocating traveller, and means connected to said latch lever and actuated by said traveller in the other direction of its movement to release the latch lever from engagement with the shifting lever and disengage the clutch mechanism from said control shaft. 70
7. In a machine of the class described, the combination with means for feeding the material to be packed, of a support for the bag to be filled movable towards and away from said feeding means, driving mechanism for said feeding means, a control shaft, clutch mechanism associated with said control shaft for controlling operation of the same, a shifting lever associated with said clutch mechanism and actuated by the bag support on its movement towards the feeding means, whereby to engage the clutch mechanism with the control shaft, means for locking said shifting lever to maintain the engaged relation of the clutch mechanism with said control shaft, a double grooved worm associated with said control shaft, a reciprocating traveller mounted on said worm and operatively related to the driving mechanism for connecting the latter with the feeding means on one direction of movement of said traveller on said worm, and means for releasing said shifting lever on the other direction of said traveller to disengage the clutch mechanism from said control shaft. 80
8. In a machine of the class described, the combination with means for feeding the material to be packed, of a support for the bag to be filled movable towards and away from said feeding means, driving mechanism for said feeding means, a control shaft, clutch mechanism associated with said control shaft for controlling operation of the same, a shifting lever associated with said clutch mechanism for engaging the latter with said control shaft, said shifting lever being operatively related to said bag support to establish driving relation of the clutch mechanism with said control shaft on movement of the bag support towards the feeding means, means for locking said shifting lever to maintain the clutch mechanism in said driving relation to said control shaft, a reciprocating traveller associated with said control shaft, a contact shoe carried by said reciprocating traveller and having operative connection with said driving mechanism to connect the latter with said feeding means on one direction of movement of said trav- 90
- eller, a rock shaft operatively related to said reciprocating traveller to be actuated by the latter on the other direction of its movement, and connections between said rock shaft and the locking mechanism of the shifting lever for actuating said locking mechanism to release the shifting lever and disconnect the driving mechanism from the feeding means. 95
9. In a machine of the class described, the combination with means for feeding the material to be packed, of a support for the bag to be filled movable towards and away from said feeding means, driving mechanism for said feeding means, a control shaft, clutch mechanism associated with said control shaft for controlling operation thereof, a shifting lever for controlling said clutch mechanism and adapted to be actuated by the bag support on its movement toward the feeding means for operating said clutch mechanism to engage the latter with said control shaft, a latch lever pivotally mounted for engagement with said shifting lever to lock the clutch mechanism in engagement with said control shaft, a reciprocating traveler associated with said control shaft, means for causing said traveler to move in one direction on said shaft and to reverse its direction of movement at a predetermined limit, a contact shoe carried by said traveler and having an inclined face, an actuating lever associated with said driving mechanism and adapted to be engaged by the inclined face of said contact shoe to 100 connect the driving mechanism with the feeding means on one direction of movement of the reciprocating traveler, and mechanism effective upon said latch lever and operated by said traveler in the other direction of its movement, whereby to release the latch lever from engagement with the shifting lever to disengage the clutch mechanism from said control shaft. 105
10. In a machine of the class described, the combination with means for feeding the material to be packed, of a support for the bag to be filled movable towards and away from said feeding means, driving mechanism for said feeding means, a control shaft, clutch mechanism for controlling operation of said control shaft, a shifting lever pivotally mounted in proximity to said clutch mechanism and connected thereto for controlling the same, said shifting lever being actuated by the bag support on its movement toward the feeding means for operating said clutch mechanism to engage the latter with said shaft, a locking toe carried by said shifting lever, a latch lever pivotally mounted for engagement with said locking toe of said shifting lever to lock the clutch mechanism in engagement with said shaft, a reciprocating traveler associated with said shaft, means for causing said traveler to 110
- 115
- 120
- 125
- 130

move in one direction on said shaft and to reverse its movement of direction, at a pre-determined limit, a contact shoe carried by said traveler and having an inclined face, 5 an actuating lever associated with said driving mechanism and adapted to be engaged by the inclined face of said contact shoe to connect the driving mechanism with the feeding means on one direction of movement 10 of the reciprocating traveler, and connections effective upon said latch lever and operated by said traveler in the other direction of its movement, whereby to release the latch lever from engagement with the shifting lever to disengage the clutch mechanism 15 from said control shaft.

11. In a packaging machine, in combination, a movable support for a receptacle, feeding mechanism for feeding material to 20 a receptacle on the support, a drive shaft, feed clutch mechanism for operably connecting the feeding mechanism with the drive shaft, and clutch control mechanism operable by the support to throw the clutch 25 in and by the drive shaft to throw the clutch out.

12. In a packaging machine, in combination, a drive shaft, a receptacle support movable to filling position independently of 30 the drive shaft, feeding mechanism for feeding material to a receptacle on the support, feed clutch mechanism for operably connecting the drive shaft and feeding mechanism, clutch control mechanism operable 35 by the drive shaft to throw the feed clutch mechanism in and out of connection, and starting means operable by the support for rendering the drive shaft effective on the clutch control mechanism.

40 13. In a packaging machine, in combination, a drive shaft, a receptacle support, feeding mechanism for feeding material to a receptacle on said support, feed clutch mechanism for operably connecting the 45 drive shaft and feeding mechanism, clutch control mechanism rendered effective

through operation of the drive shaft to disconnect the feeding mechanism therefrom independently of the receptacle support, and starting means operable by the receptacle 50 support to render the drive shaft effective on the clutch control mechanism.

14. In a packaging machine, in combination, a drive shaft, a movable receptacle support, feeding means for feeding material to 55 a receptacle on said support against resistance of the latter, feed clutch mechanism for operably connecting the drive shaft to the feeding mechanism, clutch control mechanism for shifting said clutch, means operable by the support to initiate operation of the clutch control mechanism, and means operable by the clutch control mechanism to determine its extent of operation.

15. In a packaging machine, in combination, 65 a drive shaft, feeding mechanism, a receptacle support, means for moving said receptacle support toward and from the feeding mechanism, a clutch for controlling operation of the feeding mechanism, clutch control mechanism operable by the drive shaft to release the clutch, and means operable by the support to initiate operation of the clutch control mechanism.

16. In a packaging machine, in combination, 75 a movable support for a receptacle, feeding mechanism for supplying material to a receptacle on said support, a continuously operating drive shaft, feed clutch mechanism for operably connecting said shaft to said feeding mechanism, clutch control mechanism operable by said drive shaft, and means operable by the support to render the drive shaft effective on the clutch control mechanism.

85 In testimony whereof I have hereunto subscribed my name in the presence of two subscribing witnesses.
